UNITED STATES PATENT OFFICE.

HERBERT T. HERR, OF PITTSBURGH, PENNSYLVANIA, ASSIGNOR TO WESTINGHOUSE ELECTRIC & MANUFACTURING COMPANY, A CORPORATION OF PENNSYLVANIA.

GEARED-TURBINE INSTALLATION.

1,312,907.

Specification of Letters Patent. Patented Aug. 12, 1919.

Application filed December 11, 1916. Serial No. 136,312.

To all whom it may concern:

Be it known that I, HERBERT T. HERR, a citizen of the United States, and a resident of Pittsburgh, in the county of Allegheny and State of Pennsylvania, have made a new and useful Invention in Geared-Turbine Installations, of which the following is a specification.

This invention relates to turbine apparatus and particularly to turbines adapted to be employed for marine propulsion. In marine and particularly in naval installations the space available for propelling apparatus is limited and consequently it is necessary to develop a maximum amount of power in a minimum amount of space. In addition to this, the head room is often materially limited and consequently it is difficult to so arrange the power developing apparatus that it is located in a protected position and below the armored decks. The power transmitted by a geared turbine is limited by the power capable of being transmitted by the pinion connected to the turbine. For this reason it is essential where high powers are transmitted to a shaft to divide the turbine unit into sections and to gear the separate sections to the shaft.

An object of the present invention is to produce a compact geared turbine unit which is capable of developing relatively large power and which occupies less space per unit of power developing capacity than other turbine units now in use or known to me. A further object is to produce a turbine unit in which the separate sections are geared to the same shaft by means of a common driven gear and in which the sections are so located that their interiors are readily accessible.

A further object is to produce a compact compound turbine in which the separate sections are geared to the same shaft and in which the sections are so arranged that the unit and the condenser serving it occupy a minimum amount of space.

These and other objects which will be made apparent throughout the further description of the invention are attained by means of turbine apparatus embodying the features herein described and illustrated in the drawings accompanying and forming a part hereof.

In the drawings: Figure 1 is an end view of a geared turbine apparatus embodying my invention.

Fig. 2 is a plan view of the apparatus shown in Fig. 1.

The illustrated embodiment of the invention includes a compound turbine having a high pressure and a low pressure section, both of which are geared to the same shaft by means of separate pinions and a common driven gear. The apparatus also includes a condenser which is located immediately below the low pressure section and it may include a cruising turbine which may be directly connected to the high pressure turbine.

The apparatus illustrated includes a high pressure section 3, and a low pressure section 4. The high pressure section is shown operatively coupled to a pinion 5 by means of a clutch or coupling 6, and the low pressure section is shown operatively connected to a pinion 7, by means of a clutch or coupling 6'. Both the pinions 5 and 7 mesh with a gear 8 which is operatively coupled to or mounted on the propeller shaft 10. As illustrated, the high pressure section is so located that its pinion 5 meshes with the gear 8 at a point below the longitudinal axis of the gear 8, whereas the low pressure section is so located that its pinion 7 meshes with the gear 8 at a point above the longitudinal axis of the gear and on the opposite side of the vertical axial plane of the gear from that of the pinion 5.

With this arrangement the sections are compounded across the axis of the gear and, as illustrated, the exhaust port of the high pressure section 3 is located in the top of the casing and communicates with the inlet of the section 4 through a pipe or passage 9 which extends upwardly and across the axis of the gear 8. The inlet of the low pressure section is located in one side of the casing of that section, and suitable expansion joints 10' are provided between both the turbine sections and the pipe 9.

The exhaust port of the section 4 is located in the bottom of the casing of that section and communicates with a condenser 11, which is located immediately below the section and may be suspended from it if desired. I have, however, shown an expansion joint 13, between the condenser and the exhaust port of the turbine.

In the drawings the low pressure section is shown as a double flow section, and where a double flow section is employed the casing

will, of course, be provided with two exhaust ports, both of which will communicate with the inlet port of the condenser.

As diagrammatically shown the condenser 5 is provided with a condensate offtake port 14 located in the lower portion of its shell, and adapted to communicate with a condensate pump 30, located below the condenser.

In Fig. 2 I have shown a cruising turbine 10 16 geared to the shaft of the high pressure section 3, by means of a gearing 19. It will, of course, be understood that the cruising section may be directly connected to the section 3, or that it may drive a 15 separate pinion which also meshes with the gear 8.

With the arrangement of apparatus described each separate section is not only independent and capable of being operated 20 independently in case of an accident, but by providing the ordinary divided casing the interior of each section is readily accessible.

Either or both the high and low pressure 25 sections may be provided with the usual form of reversing sections, or a separate reversing section may be employed.

For the purpose of increasing the power delivered to the propeller shaft, a unit 30 similar to the unit just described may be arranged to transmit power to the gear wheel 8. In the drawings I have illustrated such a unit as including a high pressure section 23, a low pressure section 24 35 and a separate condenser 26 serving the low pressure section. I have also shown a cruising section 29 geared to the shaft of the section 23.

It will be understood that each unit may 40 be divided into three or more sections, each driving a separate pinion which meshes with the gear 8. In the drawings, which represent a marine installation, I have shown a circulating pump 29 for the cooling 45 water of both condensers and a condensate discharge pump for withdrawing condensate from both condensers. It will, of course, be understood that a separate pump may be employed.

50 While I have described and illustrated but one embodiment of my invention, it will be apparent to those skilled in the art that various changes, modifications, additions and omissions may be made in the 55 apparatus illustrated without departing from the spirit and scope of the invention as set forth by the appended claims.

What I claim is:

1. In a marine turbine, a driven gear, a 60 turbine unit located on one side of the gear, and comprising a high pressure and a low pressure section, one located below and on one side of the axis of the gear and the other above and on the other side of 65 the axis of the gear, a passage connecting

said sections, a separate pinion driven by each section and meshing with the gear, and a condenser communicating with said low pressure section.

2. In a marine turbine, a driven gear, a 70 high pressure section located below and on one side of the axis of the gear, a low pressure section located above and on the other side of the axis of the gear, a condenser located below the low pressure section, a 75 passage connecting said sections, and separate pinions driven by said sections and meshing with said gear.

3. In a marine turbine, a driven gear, a 80 turbine unit located in front of the gear and comprising a high pressure section located below and on one side of the axis of the gear, a low pressure section located above and on the opposite side of the axis of the gear, a pipe connecting said sections, 85 a similar unit located behind the gear, and separate pinions driven by said sections and meshing with said gear.

4. In a marine turbine installation, a driven gear, a turbine unit located in front 90 of the gear and comprising a high pressure section located with its axis below the axis of the gear and on one side thereof, a low pressure section located with its axis above the axis of the gear and on the other side thereof, a pipe connecting said sections, a condenser located immediately below the low pressure section, a similar unit and condenser located behind the gear, and separate pinions driven by said sections and meshing with said gear. 100

5. In a marine turbine installation, a driven gear, a turbine unit located in front of the gear and comprising a high pressure section located with its axis below and on one side of the axis of the gear, a low pressure section located above and on the other side of the axis of the gear, a pipe connecting the turbine sections and passing above and across the axis of the gear, an 105 expansion joint therein, a condenser located immediately below the low pressure section, a similar unit and condenser located behind the gear, and separate pinions driven by said sections and meshing with said gear. 110

6. In a marine turbine installation, a driven gear, a turbine located in front of the gear and comprising a high pressure section located below and on one side of the axis of the gear, a low pressure section located above and on the opposite side of the axis of the gear, a pipe connecting said sections, a condenser located below the low pressure section, condenser auxiliaries located below said condenser and in part directly below the axis of the gear, a similar unit and condenser located behind the gear, and separate pinions driven by said sections and meshing with said gear. 120 125 130

7. In a marine turbine, a driven gear, a turbine unit located in front of the gear and comprising a high pressure section located below and on one side of the axis 5 of the gear, a low pressure section located above and on the opposite side of the axis of the gear, a pipe connecting said sections; a similar unit located behind the gear, and separate pinions driven by said sections and

meshing with said gear, the pinions of each 10 unit being disposed with relation to the said gear substantially diametrically opposite one another.

In testimony whereof, I have hereunto subscribed my name this 9th day of De- 15 cember, 1916.

HERBERT T. HERR.
